US0D1100818S

(12) **United States Design Patent** (10) Patent No.: **US D1,100,818 S**
 Bernard et al. (45) Date of Patent: ** Nov. 4, 2025

(54) **CHARGER FOR A WEARABLE DEVICE**(71) Applicant: **Google LLC**, Mountain View, CA (US)(72) Inventors: **Cédric Eric Jean-Edouard Bernard**, San Francisco, CA (US); **Junyong Park**, San Francisco, CA (US); **Eric John Fairbanks**, Lafayette, CA (US); **Benjamin Patrick Robert Jean Riot**, Alamo, CA (US); **Anthony Gerald Kern**, San Francisco, CA (US)(73) Assignee: **Google LLC**, Mountain, CA (US)(***) Term: **15 Years**(21) Appl. No.: **29/807,178**(22) Filed: **Sep. 9, 2021****Related U.S. Application Data**

(63) Continuation of application No. 29/779,472, filed on Apr. 19, 2021, now abandoned.

(57) **CLAIM**

The ornamental design for a charger for a wearable device, as shown and described.

DESCRIPTION

FIG. 1 is a top, front, right side perspective view of a first embodiment of a charger for a wearable device showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a back view thereof;

FIG. 8 is a cross-sectional view along line 8-8 identified in FIG. 2;

FIG. 9 is a cross-sectional view along line 9-9 identified in FIG. 2;

FIG. 10 is a top, front, right side perspective view of a second embodiment of a charger for a wearable device showing our new design;

FIG. 11 is a top view thereof;

FIG. 12 is a bottom view thereof;

FIG. 13 is a left side view thereof;

FIG. 14 is a right side view thereof;

FIG. 15 is a front view thereof;

FIG. 16 is a back view thereof;

FIG. 17 is a cross-sectional view along line 17-17 identified in FIG. 11;

FIG. 18 is a cross-sectional view along line 18-18 identified in FIG. 11;

FIG. 19 is a top, front, right side perspective view of a third embodiment of a charger for a wearable device showing our new design;

FIG. 20 is a top view thereof;

FIG. 21 is a bottom view thereof;

FIG. 22 is a left side view thereof;

FIG. 23 is a right side view thereof;

FIG. 24 is a front view thereof;

FIG. 25 is a back view thereof;

FIG. 26 is a cross-sectional view along line 26-26 identified in FIG. 20; and,

FIG. 27 is a cross-sectional view along line 27-27 identified in FIG. 20.

The broken lines in the drawings illustrate both environment and portions of the article that form no part of the claimed design.
